UNITED STATES PATENT OFFICE.

EARL C. VAN VALKENBURG, OF HOLYOKE, MASSACHUSETTS.

COLLAPSIBLE-TUBE CLOSURE.

Application filed December 24, 1923. Serial No. 682,576.

This invention relates to improvements in collapsible tube closures and its leading object is to provide a collapsible tube closure so constructed that it will act not merely to close the discharge orifice of the tube but to sever the extruded material by the operation of closing the orifice.

With the above and other objects in view the invention relates to certain new and useful constructions, combinations and arrangements in parts, clearly described in the following specification and fully illustrated in the accompanying drawings in which:

Fig. 1 is a side elevation of a collapsible tube constructed in accordance with my invention.

Fig. 2 is a top plan view thereof, showing the closure in closed position.

Fig. 3 is a similar view showing the closure in open position.

Fig. 4 is a side elevation showing the closure in the cutting off position.

Fig. 5 is a detail vertical transverse sectional view of a modified form.

Fig. 6 is a vertical longitudinal sectional view thereof.

Referring to the accompanying drawings 5 designates a collapsible tube of the usual type having an end closure 6 secured to one 30 end thereof and a circular head 7 formed in the opposite end and provided with a centrally located orifice 8. The head 7 is preferably tapered in the usual manner and is provided with an integral guide 9. The 35 guide 9 is preferably formed with grooves 10 and 11 on the opposite sides thereof, which sides are disposed in parallel lines to each other and the upper surface of the guide is disposed in parallel lines to the 40 side faces of the guide. The orifice 8 extends through the guide, and across the orifice the closure member 12 is designed to slide.

The closure member 12 is preferably 45 formed from sheet or strip metal and is provided with retaining flanges or ribs 13 and 14 designed to engage the grooves 10 and 11 respectively. The member 12 is also provided on its rear end with finger 50 coils and lugs 15 and 16 designed to permit of the operation of the device. In order to retain the member 12 for limited sliding movement upon the guide, a slot 17 is formed in one or both sides of the guide 55 and through this slot a retaining pin 18 car-

ried by the closure member is extended into the body of the guide so as to retain the closure member for limited sliding movement across the orifice 8.

The limit of such movement is controlled 60 by the length of the slot 17, so that in its open position the closure member 12 would entirely clear the orifice 8. When the closure member is shifted across the orifice 8 from its open position to its closed position, 65 the strip or ribbon of material exuded from the collapsible tube will be cut off by the closure member and the orifice 8 will be closed at the same time. Due to the snug fitting engagement of the closure member 12 70 with the guide the orifice will be snugly closed when the closure is positioned over the orifice.

In Figs. 5 and 6 I show a modified form 75 wherein the top wall 20 of the closure is formed with an integral stop 21 which may be stamped therefrom or drawn from the metal of which the closure is composed. This stop 21 is designed to reciprocate in a groove 22 formed in the guide 23. 80

The closure is provided with side walls 24^a and 24^b, the side wall 24^a being formed with a longitudinal grooved portion 24^a and the side wall 24^b being formed with a similar portion 25^a. The grooved portion 24^a slidably 85 engages the grooved portion 24^b and the grooved portion 25^a slidably engages the grooved portion 25^b formed in the guide 23 which is integral with the collapsible tube 5' which is formed with the usual orifice 8'. 90

Having described my invention, I claim:

In combination, a paste holding collapsible tube having a neck provided with an opening and an integral guide extending from the opening and provided with parallel side faces having external grooves 95 therein, and also provided with a flat end face, having an external groove providing stops, and a sheet metal closure having side flanges slidably engaging the parallel side 100 faces and provided with means slidably interlocking with said external grooves first named, the closure having a stop to slidably fit in the groove of the end face and engage the stops thereof, the closure having a knife 105 cutting action on any ejected contents of the tube.

Signed by me at Holyoke, Mass.

EARL C. VAN VALKENBURG,
